**APPARATUS FOR SORTING ARTICLES HAVING
AN ASYMMETRICAL END**

George V. Martin, Berwyn, Ill., assignor to Western Electric Company, Incorporated, New York, N.Y., a corporation of New York

Filed Jan. 7, 1963, Ser. No. 249,899
1 Claim. (Cl. 209—74)

The present invention relates generally to sorting apparatus, and more particularly to apparatus for sorting articles having an end which is asymmetrical with respect to a centerline of the article.

Despite great technological advances in the manufacturing and assembling arts, industry is still plagued with the intricate task of sorting component parts so that only properly oriented parts are presented for insertion into an assembly. The shapes and sizes of such parts vary greatly, complicating the problem grossly, and though every sorting device must have regard for the shape and size of a particular part, few devices have regard for a broad category of sizes and shapes so as to be operable on all such parts. Further, even fewer devices take advantage of such inherent characteristics as shape and size to cooperate so intimately that the parts, in effect, sort themselves.

Accordingly, the general objects of the present invention are to provide new and improved apparatus for sorting articles having an asymmetrical end, and more specifically, articles having an end which is asymmetrical with respect to a longitudinal centerline of the article.

Further objects of the invention are to provide new and improved apparatus for sorting articles having an asymmetrical end with respect to a centerline of the article, which apparatus utilizes advantageously and actively the inherent configuration of the article to cooperate in effecting the sorting operation.

The particular application contemplated for such apparatus involves the insertion of an insert, having inwardly directed serrations, into a close-fitting shell in the assembly of an electrical crimp connector. Such shells must be sorted and fed into the assembly apparatus in a particular orientation (namely, with a beveled open end presented last and at a particular disposition, to the inserting apparatus) or else insertion of the insert into the shell cannot be effected.

Several problems arise in connection with the sorting of such shells, stemming from the smallness in size of the shell and from the large number of possible orientations the shells can assume. Specifically, the shells have a pair of opposed plane side walls and a pair of arcuate side walls, the beveled open end and a rounded closed end; thus, each shell can assume eight possible orientations, each of which varies the handling requirements. To further complicate matters, the sorting apparatus must be virtually infallible, since improperly oriented shells jam the inserting apparatus. In addition, the shells must be sorted very rapidly in order to keep pace with the inserting apparatus which handles shells at a rate of approximately 100 shells per minute.

Therefore, more specific objects of the invention are to provide new and improved apparatus for sorting articles having an asymmetrical end, which apparatus utilizes the inherent configuration of the article to cooperate actively with the apparatus to effect the sorting operation, and which apparatus effects the sorting operation efficiently, effectively, and expediently, and with fail-safe accuracy and dependability.

Apparatus in accordance with the invention and accomplishing the above objects, includes a first and second rotatable means spaced apart and resiliently biased relatively together so that generally continuous peripheral

2

surfaces thereof are disposed in facing relationship and define a restrictive throat therebetween. A mechanism is provided for driving an article having an asymmetrical end through the restrictive throat generally in the direction of the centerline of asymmetry, the peripheral surfaces defining the restrictive throat normally being spaced apart a distance less than the corresponding dimension of an article so driven such that the rotatable means yield against the biasing force thereon when an article is driven therebetween. With such apparatus, articles having the asymmetrical end dispensed last from between the rotatable means are deflected angularly toward the rotatable means which cleaves longest to the edges of the article.

In accordance with a preferred embodiment of the invention, the first and second rotatable means comprise a pair of rollers, one of which is mounted for limited movement toward and away from the other and is resiliently biased toward the other. Further, the driving mechanism acts upon the articles by rotating the rollers in synchronism and in opposite directions, so that articles fed into the restrictive throat are gripped, drawn between, and dispensed from the rollers.

Other objects, advantages and aspects of the invention will appear from the following detailed description of a specific embodiment thereof when taken in conjunction with the appended drawings, in which:

FIG. 1 is an enlarged plan view of an article acted upon in the sorting operation of a preferred application of the invention;

FIG. 2 is a sectional view of the article, taken generally along the line 2—2 in FIG. 1;

FIG. 3 is an elevational view of a preferred embodiment of the invention; and

FIG. 4 is a sectional view of the preferred embodiment taken generally along the line 4—4 in FIG. 3.

It is necessary at the outset to discuss the general category of articles upon which the invention is intended to be operative, because the apparatus relies upon certain characteristics in the configuration of the article for cooperation in effecting the sorting operation. Basically, the articles contemplated are those having an end which is asymmetrical with respect to any centerline of the article, but it is preferably that the axis of asymmetry be the longitudinal centerline of the article for reasons which will become apparent from the description which follows.

An article 10 exemplary of this configuration is featured in FIGS. 1 and 2, and is composed of a pair of arcuate side walls 11—11 and a pair of plane side walls 12 and 13, which are convergent at one end and form a rounded nose portion 14. The arcuate side walls 11—11 are beveled at an open end 16 of the article 10, and consequently the plane side walls 12 and 13 are of unequal lengths—side wall 12 being the shorter of the two.

Each article 10 composes the shell of an electrical crimp connector, and are to be fed to an inserting apparatus wherein a snug-fitting insert is inserted therewithin. The inherent configuration of the shells requires that successive shells being fed to the inserting apparatus be oriented in a particular manner, that is, the beveled open end thereof must be presented last and in a particular disposition, to the inserting apparatus, in order to permit proper reception of the insert within the shell.

The above-mentioned characteristics of the article 10 are of paramount importance in the invention for effecting the sorting of the articles for proper presentation to the inserting apparatus. To recapitulate, therefore, the article 10 has a symmetrical end, formed by the rounded nose portion 14, and an asymmetrical end, formed by the beveled end 16, with respect to the longitudinal centerline, designated A in FIG. 1, of the article.

Turning now to the sorting apparatus, depicted in FIG. 3, the articles 10—10 are initially received in the upper

end of a vertical feed tube 17. Articles received in the tube 17, fall by gravity into a restrictive throat 18 defined between opposed peripheral surfaces 19 and 20 of a pair of gripping rollers 21 and 22. The tube 17 is designed with a configuration conforming to that of the article 10 so that the articles are received in the restrictive throat 18 with the plane side walls 12 and 13 facing towards the rollers 21 and 22.

The rollers 21 and 22 are spaced apart with the peripheral surfaces 19 and 20 separated by a distance slightly less than the width W of the article 10, across the plane sides 12 and 13 (FIG. 1), and are provided with a certain amount of resiliency as will be described in detail below. Thus, when rotated in synchronism in the appropriate directions by a drive mechanism 23, the rollers 21 and 22 yield slightly to grip the plane sides 12 and 13 of an article 10 received in the restrictive throat 18 and draw the article therethrough. Such action of the rollers 21 and 22 also provides a valve mechanism for the feed tube 17, permitting articles 10-10 to be received within the restrictive throat 18 only one at a time, as the preceding article is being drawn between the rollers.

Having oriented the article 10 with the plane side walls 12 and 13 facing the rollers 21 and 22, there remains three orientations of the article to be deciphered and separated by the sorting apparatus. Specifically, articles having the asymmetrical, beveled end pointed up must be separated from articles having it pointed down, and beveled-end-up articles must further be divided into groups with the bevel pointed exclusively to the left or to the right. The beveled-end-down articles need not be separated into two groups because they must be turned end for end and recycled through the sorting apparatus before they can be properly presented to the inserting apparatus.

With regard to the rollers 21 and 22, the directions up and down contradistinguish articles having the beveled end dispensed last and first from between the rollers, respectively. Bearing this in mind, articles dispensed from the rollers 21 and 22 with the nose portion 14 last, fall undeflected into a central repository tube 24 vertically disposed in alignment beneath the restrictive throat 18. Such articles are dispensed undeflected because the plane sides 12 and 13 of the nose portion 14, which is symmetrical about the longitudinal centerline, sever contact with the peripheral surfaces 19 and 20 of the rollers 21 and 22 simultaneously. That is, because of the symmetry of the nose portion 14, neither roller exerts an independent influence on the article 10. As stated above, these articles 10-10 are turned end for end and recycled through the sorting apparatus.

However, articles 10-10 with the asymmetrical or beveled end 16 dispensed last from the rollers 21 and 22, are deflected either to the left or to the right, depending upon whether the beveled end is pointed to the left or to the right, respectively. Specifically, articles 10-10 drawn through the restrictive throat 18 with the beveled end 16 pointed upward and to the left are dispensed with a deflection to the left because the peripheral surface 20 of the roller severs contact with the side 12, because it is shorter, while the roller 21 continues momentarily in contact with the side 13. Consequently, the roller 21 exerts an independent influence on the article 10 and the combined action of the resiliency and the rotation of the roller 21 imparts a tangential thrust to the article, deflecting it slightly to the left. Likewise, articles 10-10 having the beveled end 16 pointed upward and to the right are imparted with a tangential thrust deflecting them to the right because this time the roller 22 exerts an independent influence on the article by momentarily delayed severing of contact with the longer side 13.

The articles deflected to the left or to the right are respectively received in one of a pair of angular repository tubes 25 and 26 disposed beneath the rollers 21 and 22 in alignment with the respective direction of deflection X

or Y to the left or to the right. The directions of deflection X and Y may be predicted as closely approximating a line tangent to the roller exerting independent influence, at the point around its circumference where the article 5 severs contact therewith. The spacing of the tubes 25 and 26 beneath the rollers 21 and 22 is determined by the length of the article 10, and is calculated such that as the article is deflected outwardly, it will clear the innermost wall 27 of the respective tube, but will engage the outermost wall 28. The tangential thrust in combination with 10 gravity, thereafter propel the article into that tube while the initial orientation of the plane side walls 12 and 13 is maintained.

Thus, the sorting apparatus utilized in this preferred 15 application separates articles having a beveled end thereof pointing up from articles having it pointed down, and further divides the bevel-end-up articles into a first group with the beveled end pointing toward the left and a second group having that end pointing toward the right. As 20 a result, the bevel-end-up articles with the bevel in the proper disposition, may be fed directly to the inserting apparatus. The beveled-end-up articles with the bevel wrongly disposed, need only be turned side for side 180 degrees before they also may be fed to the inserting apparatus. Finally, the beveled-end-down articles are 25 turned end for end and recycled through the sorting apparatus, and then they too may be fed to the inserting apparatus. It will be noted in that respect, that the sorting apparatus is completely fail safe in that only beveled-end-up articles can possibly be deflected, and if for some 30 reason one of them is not, it is merely recycled through the sorting apparatus.

In order to accomplish the above sorting operation so 35 that all articles will be properly deflected, it is desirable that the rollers be given a certain amount of resiliency, inherent or extrinsic, so that articles drawn therebetween are gripped firmly thereby, yet not deformed. One manner in which this may be accomplished is by fabricating the rollers 21 and 22 out of a resilient material, such as 40 rubber, or by providing a resilient material around the peripheral surfaces 19 and 20, which material deforms when an article is drawn between the rollers and thereby both resiliently and frictionally engages the adjacent edges of the article to exert proper influence thereover.

Preferably, such resiliency is provided extrinsically by 45 allowing one of the rollers to float a predetermined distance horizontally, relative to the other roller, but also providing a continuous biasing force on the floating roller toward the other roller. This is accomplished by mounting the rollers 21 and 22 for rotation with horizontal shifts 29 and 30, respectively; the shaft 29 and attached roller 21 being coupled directly to a motor 31. The shaft 30 and attached roller 22 are driven in synchronism with, but in a direction contrary to, the shaft 29 and the roller 21 by a pair of gears 32-32, one mounted securely to each of the shafts and engaged with the other.

The shaft 30 is rotatably mounted in a float member 33 50 slidably mounted on a pair of spaced pins 34-34 projecting horizontally from a support standard 35, the pins being received in a pair of slots 36-36. The lengths of the slots 36-36 define the predetermined distance the roller 22 is to float relative to the roller 21, and are such that the gears 32-32 cannot disengage from each other. The float member 33 is biased toward the shaft 29 (to the left as viewed in FIG. 3) by a spring 37 mounted in 55 the support standard 35. In this manner the rollers 21 and 22 are rotated in synchronism in opposite directions, and are provided with an extrinsic resiliency which insures a proper influence of the rollers on an article 10.

Thus, when the rollers 21 and 22 are rotated in such 60 directions as to draw an article 10 through the restrictive throat 18 therebetween (roller 21, clockwise, and roller 22, counterclockwise—as viewed in FIG. 3), the roller 22 floats horizontally away from the roller 21 (to the right) only that amount required to permit the article 10

to pass therebetween while the rollers maintain gripping contact with the article due to the action of the spring 37.

While one specific embodiment is described in detail hereinabove, various modifications may be made without departing from the spirit and the scope of the invention. 5

What is claimed is:

Apparatus for sorting articles having an asymmetrical end and a symmetrical end, relative to a longitudinal centerline of the article, which comprises:

- a pair of rollers disposed for rotation about horizontal axes, and spaced apart to define a restrictive throat with the peripheral surfaces thereof in facing relationship and normally separated by a distance less than the width of an article; 10
- a gravity feed tube mounted in vertical alignment above the restrictive throat for feeding articles one at a time lengthwise into the restrictive throat with a predetermined orientation; 15
- first and second gears each coupled directly to an associated one of said rollers and arranged in meshing engagement with each other; 20
- means for rotating one of said gears, which rotation is transmitted to the associated roller and through the other of said gears to its associated roller so that said rollers are rotated in synchronism and in opposite directions; 25
- means for supporting one of said rollers and attached gear for limited translational movement away from the other roller and attached gear to the extent that said respective gears are not disengaged; 30

resilient means for biasing said one roller and attached gear toward said other roller and attached gear, said resilient means being compressed as an article is drawn between the rollers and exerting a force on said one roller such that articles dispensed from between said rollers with the asymmetrical end last are angularly deflected toward the roller which cleaves longest to the edges of the article because of such asymmetry, and such that articles dispensed with the symmetrical end last continue with an undeflected course because of such symmetry; and a pair of repository chutes disposed at discrete angles to and in close proximity beneath said rollers, the angles at which said chutes are disposed being such that articles deflected angularly toward one or the other of said rollers are propelled into an associated one of said repository chutes, while articles dispensed with an undeflected course are propelled between said repository chutes.
